UNITED STATES PATENT OFFICE.

JULES WERY, OF DEERFIELD, ILLINOIS.

CAN-SEAMING MACHINE.

Application filed March 8, 1928. Serial No. 260,002.

This invention relates to can seaming or closing machines and it has among its objects the provision of a light, simple, efficient and positively acting machine for tightly closing the covers on cans by a double seam, the new machine being particularly suitable for hand operation although not altogether restricted thereto.

The objects of the invention will be best understood from the following description of an embodiment thereof, reference being had to the accompanying drawings, wherein

Fig. 1 is a front elevation of a machine embodying the invention with a can in seaming position;

Fig. 2 is a plan view of the machine;

Fig. 3 is a sectional view through the seaming roller support along lines 3—3 in Fig. 2;

Fig. 4 is a fragmentary sectional view of a can section, the cover and the associated portions of the seaming machine in position to begin the seaming operation;

Fig. 5 is a view similar to Fig. 4 illustrating the position of the first or preliminary seaming roller and the can portion upon which it acts at the end of the preliminary seaming operation;

Fig. 6 is a view similar to Fig. 4 illustrating the finishing seaming roller and the can portion upon which it acts in the course of the finishing seaming operation;

Fig. 7 is an enlarged plan view of the seaming roller mechanism of the machine in Fig. 1;

Fig. 8 is a view similar to Fig. 7 showing the parts in disassembled condition;

Fig. 9 is a vertical sectional view through the seaming roller mechanism along the lines 9—9 in Fig. 7; and

Fig. 10 is a vertical sectional view through the driving chuck support and associated operating mechanism along the lines 10—10 in Fig. 2.

The invention will be explained by reference to an embodiment thereof in a hand operated machine as shown in the drawing. Referring to Figs. 1 and 2 the machine comprises a U-shaped frame member 11, consisting of a lower cross member 12 and two upright posts 13 and 14. The lower portion of the frame 11 is provided with suitable U-shaped clamps 15 of familiar design by means of which the entire machine may be firmly clamped to a bench, or the like, when using the machine. The entire frame with the

clamps 15 is preferably made on a single piece of metal by die-casting, for instance.

On the cross member 12 of the frame is mounted the lifter plate 16 of the machine with the associated lifter mechanism. The 60 lifter mechanism comprises a round lifter pin 17 longitudinally slidable in a perforated, enlarged bearing member 18 of the frame, and a circular lifter cam 19 freely slidable on the pin 17 and having an inclined cam surface 65 20 co-operating with a similar cam surface 21 on the upper end of the bearing 18. The cam 19 is provided with a cam lever 23 by means of which the cam 19 may be rotated around the pin 17, thereby causing the cam 70 19 to be forced upwardly along the inclined cam surfaces 20, 21. The upper end of the pin 17 is provided with a collar 25 by means of which the pin is held in place above the cam 19, a pair of washers 26 interposed between the cam and the collar 25 serving to secure the correct spacing. One of these washers 26 is of a suitable, resilient, cushioning material, such as rubber, to permit proper application of pressure to the can in the manner hereinafter described.

The lifter pin 17 forms a short stud extending above the collar and fitting into a central perforation in the lifter plate 16 so as to hold the same in place. The lifter plate 16 constitutes a substantially rigid disk-like member provided with a plurality of concentric grooves 31, 32, 33 for receiving the projecting edges of the lower closed ends of various sizes of cans which are to be seamed on the 90 machine. In the example illustrated, three such concentric grooves are shown, each for receiving a different size of can. A medium size can having its lower end fitting the second groove from the center is shown in position on the drawing.

In commercial practice there is a limited standard number of can sizes and the grooves are so arranged as to fit the various sizes of the cans which are on the market, a single lifter plate being sufficient for use on all the standard can sizes. Variations in the height of the can are taken care of by adding additional washers between the collar 25 and the upper cam surface 21 or by using washers of 105 different height.

The cam surfaces 20 and 21 have in addition to the inclined portions also parallel portions corresponding to the lowest and highest position of the lifter plate. In Fig. 110

1 the lifting lever and can are shown in raised position brought about by rotating the lever to the left. By turning the lever to the right the lifter plate may be lowered. The upper 5 ends of the uprights 13 of the frame terminate in threaded studs 35, 36 which fit into perforations in a transverse member 37 which forms an upper cross member for the frame, the transverse member being held in place 10 by means of nuts 38.

The upper frame member 37 is provided with a bearing 41 located directly above the lower bearing 18. In this upper bearing 41 is mounted a chuck spindle 42 to the 15 upper end of which is bolted a bevel gear 43. The chuck spindle 42 is held in place by an enlarged head portion 45 acting on the under surface of the bearing 41. To the under surface of the chuck spindle 42 is clamped by 20 means of a countersunk screw 46 a driving chuck plate 47 having an outer circular knurled rim, adapted to engage the inner portion of the can cover as shown in detail in Fig. 10. The driving chuck plate 47 is prevented 25 from rotation against the chuck spindle 42 by means of pins 49 secured to the spindle 42 and fitting into suitable holes in the chuck plate.

As seen in Fig. 10, the chuck plate 47 may 30 be readily removed or replaced by another plate by simply loosening the single screw 46 by which it is clamped in place. Accordingly one driving chuck plate may be readily replaced by another driving chuck plate corresponding to the different sizes of the covers on the cans that are to be closed without extended manipulation on the machine. The driving chuck plate is arranged to be rotated by means of a pinion 51 engaging the bevel gear 43, the pinion being rotated by a shaft 52 journaled on two upstanding lugs 53 of the upper transverse member. A crank 54 mounted on the free end of the shaft 52 serves to rotate the same.

In order to perform seaming operations a can 55 as shown in Fig. 1 is placed on the top of the lifter plate 16 with the lower edges of the can fitting in a groove corresponding to its size, the lifting lever 23 being to the right 45 with the lifting cam in its lowest position. With the can so located in place the lifting lever 23 is turned to the left, thereby raising the can on the upper opening of which a can cover, as shown in detail in Fig. 10 and Fig. 4, 50 previously was placed. This forces the driving chuck plate into the depression formed by the can cover 57 and brings the outer rim thereof into engagement with the vertical inner rim portion 58 of the cover. In forcing 55 the can into its upper position the driving chuck tends to bring the initially flat outer edge of the can into the curl of the seam fold on the outer edge of the cover. The use of the substantially rigid lifter plate 16 combined with the resiliency afforded through the

interposed rubber washer 26 materially assists in securing proper alignment of the edges of the can and of the cover that are to be seamed. The resilient rubber washer permits the slight shortening of the can accompanying this infolding operation while maintaining the entire can in fixed position and locating it positively relative to the rim of the driving chuck plate.

In order to secure reliable and accurate 75 double seaming of the can and cover edges, I utilize a novel seaming mechanism 60 including a pair of seaming rollers 61 and 62 mounted on a seaming roller supporting plate 63, as shown in detail in Figs. 3 and 7 to 9. 80 There are two seaming rollers, the preliminary seaming roller 61 and the finishing seaming roller 62. Each seaming roller is rotatably mounted between a pair of jaws 65 on a rectangularly-shaped roller carrier 66 fitting into a rectangular groove 67 on the upper side of the supporting plate 63. The roller is freely rotatable on a pin 68 fixed between the jaws 65. The upper side of the roller carrier is flush with the upper surface of the supporting plate, the latter constituting two enlarged chambers 69 in which the rollers with the associated carriers have positive longitudinal sliding movement and guidance. 85 Each carrier has a rear or tail portion 72 of 90 reduced thickness substantially corresponding to the thickness of the lower jaw.

The upper surface of the rear portion of the supporting plate is substantially flush with the upper surface of the tail portions of the 100 carriers.

Resting directly on the upper surface of the rear portion of the supporting plate is a segmental driving plate 75 that is centrally journaled on a hollow pin 76 extending through a 105 suitable perforation in the supporting plate 63. The thickness of the driving plate corresponds approximately to the height of a seaming roller, and the upper surface of the driving plate is accordingly below the level 110 of the front portion of the supporting plate by an amount corresponding approximately to the thickness of the upper jaws on the roller carriers.

The segmental driving plate 75 is further 115 provided with two sets of pin holes 81 and 82 arranged to receive pins 83 on two links 84 and 85, constituting the driving connection between the carriers 66 of the two seaming rollers and driving plate 75. The thickness of the links corresponds approximately to the thickness of the upper jaw of the carrier so that when the links are in place the lower surfaces thereof are on the level of the upper surface of the driving plate and the upper 120 surfaces of the links are on the level of the upper surface of the front portion of the supporting plate and of the carriers. The front ends of the links are provided with perforations 86 fitting and engaging pins 87 ex- 125 130

tending from a depressed part 88 on the front portion of the carriers. The rear pin 83 on the links 84 and 85 may have the form of a removable screw pin 89 mounted in a co-
 5 operating perforation in the rear portion of the links. The rear ends of the side walls 91 constituting the guiding grooves for the seaming rollers and carriers form stops 93 for the front edges 94 of the segmental driving plate 75, small adjusting screws 95 threaded into the rear ends of the side walls 91 permitting close setting of the stopping points. The guiding grooves of the carriers 66 are somewhat cut away in the rear, at 96, to per-
 10 mit lateral swinging movement of the links when actuated by the driving segment 75. A lever 99 on the driving segment permits swinging or rocking thereof around the pin 76 in either one or the other direction.
 15 The driving mechanism described above is so arranged that when in assembled condition it has two parallel flat upper and lower bound-
 20 ing surfaces, as shown in Figs. 3 and 9. By rocking the lever 99 around the pin 76 either one of the roller carriers 66 may be slid for-
 25 ward in its guide groove on the supporting plate, the other carrier and roller being at the same time withdrawn to the rear. By placing the rear pin of the link in any one of 30 the different holes 81 and 82, respectively, the limits of the movement of the carriers and the associated seaming rollers may be varied and its forward position readily advanced or brought back. The entire seaming roller
 35 mechanism is arranged for mounting of the under side of the transverse member 37 and so dimensioned that the seaming rollers may be brought into action against the seaming edges of the can top that are to be seamed,
 40 as indicated in Fig. 1 and Figs. 4 to 6.

In the example shown in the drawing this is effected by sliding the supporting plate with the hollow pin 76 over the stud 35 on the upright 13 of the frame prior to mounting the transverse member 37 in place. An additional screw 101 threaded through a perforation in the transverse member 37 into a threaded hole 102 on the middle rib 103 of the sup-
 45 porting plate definitely locates the position of the plate with respect to the frame and holds it firmly in place.

With the foregoing arrangement the seaming operation is carried on as follows:

After placing the can in raised position by means of the lifter lever, as explained above, the crank 54 is rotated thereby rotating the driving chuck plate and therethrough the can and its lower support. Thereupon the seaming lever 99 is swung to the right, as viewed in Figs. 1 and 2 bringing first the preliminary seaming roller 61 against the seaming edges of the can top and turning the same until the lever 99 has been fully brought to a stop by abutment against the stopping pin
 55 95. With the lever in this position the can is

rotated several times until the folds of the seaming edges have been fully brought into the position as determined by the contour of the preliminary seaming roller. This is the position indicated approximately on Fig. 5 70 of the drawing.

With this preliminary seaming operation performed the lever 99 is then swung to the left withdrawing the preliminary seaming roller from the can top and bringing against it the finishing seaming roller 62, thereby compressing the formed seams and completing the hermetical double seam joint between the can top and the can. The pressure on the lever 99 is continued until it is brought to a stop by abutment against the other stopping pin 95 in which position the can is given several turns in order to perfect the seam. This finishes the seaming operation and the can may be released by pushing the lever 99 85 to neutral position and lowering the lifter plate 16.

The foregoing arrangement permits ready adaptation of the machine for closing different sizes of cans without dismantling or tak- 90 ing the same apart. For instance, if a can of a next larger size than that shown in the drawing is desired to be closed, the screw 46 is loosened and another driving plate 47 of somewhat larger diameter is mounted on the 95 chuck spindle 42 in place of that shown in the drawing. Thereupon the pin screws 89 are loosened and the perforations in the rear portions of the links are brought over holes 81, 82 on the driving plate 75 corresponding 100 to the larger size can, whereupon the pin screws 89 are again screwed in place into the links locking the links into driving engagement with the driving plate. The holes 81, 82 are so positioned that each pair of holes 105 corresponds to one particular size of can just as the grooves 31 to 33 in the lifter plate 16 correspond to each particular size of can. In this way the range of forward movement of the two seaming rollers may be readily 110 adjusted for the different sizes of the cans that are to be closed without dismantling the machine.

The machine of the foregoing construction is highly efficient and permits quick seaming 115 of cans as well as rapid adjustment of seaming operations conforming to various sizes of cans. The particular construction of the seaming mechanism is instrumental in securing perfect closure and seaming of the cans. 120

My invention is not limited to the particu- 125 lar details of construction and arrangements described hereinabove but is susceptible of many modifications. I accordingly desire that the appended claims be given a broad construction commensurate with the scope of the invention.

I claim:

1. In a can seaming machine, a seaming mechanism comprising a supporting member, 130

a plurality of seaming rollers arranged to be guided on said supporting member, a driving member, a driving connection between said driving member and said rollers arranged to alternately move the same to forward or rear position, and means for independently limiting the range of the forward movement of said rollers.

2. In a can seaming machine, a seaming mechanism comprising a supporting member, a plurality of seaming rollers arranged to be guided on said supporting member, a driving member, a driving connection between said driving member and said rollers arranged to alternately move the same to forward or rear position, and means for independently varying the limits of the movement of said rollers.

3. In a can seaming machine, a supporting member, a plurality of seaming rollers arranged to be guided on said supporting member, a driving member, links connecting said rollers to said driving member, and means for independently limiting the range of the forward movement of said rollers.

4. In a can seaming machine, a supporting member, a plurality of seaming rollers arranged to be guided on said supporting member, a driving member, connecting links between said seaming rollers and said driving member arranged to alternately bring said rollers to forward position, and means for independently limiting the range of the forward movement of said rollers.

5. In a can seaming machine, a supporting member, a plurality of seaming rollers arranged to be guided on said supporting member, a driving member, and connecting links between said seaming rollers and said driving member arranged to alternately bring said rollers to forward position, said links being arranged to be adjustably positioned on said driving member to vary the limit of the forward movement of said rollers.

6. In a can seaming machine, a supporting frame, a pair of seaming rollers arranged to be guided on said frame for performing seaming operations, a driving member for said seaming rollers for alternately bringing the same to forward—seaming or rear—inoperative position, and a driving connection between said seaming rollers and said driving means to independently vary the range of the forward movement of said seaming rollers.

7. In a can seaming machine, a supporting frame, a pair of seaming rollers arranged to be guided on said frame for performing seaming operations, a driving member for said seaming rollers for alternately bringing the same to forward—seaming or rear—inoperative position, and a driving connection between said seaming rollers and said driving means arranged to independently vary the

range of the forward movement of each of 65 said seaming rollers.

8. In a can seaming machine of the class described, a frame, a driving chuck plate on said frame, a substantially rigid lifter plate mounted opposite said chuck plate on said frame, and a driving mechanism for said lifter plate comprising a lifter pin journaled in said frame, a circular cam on said pin, and a washer of resilient substance on said pin for transmitting the action of said cam on said 75 lifter plate.

9. In a can seaming machine of the class described, a supporting frame, a transverse member on one side of the frame, a driving chuck plate mounted on said transverse member, a lifter plate on said frame opposite said chuck plate, means supported on said transverse member for rotatably driving said chuck plate, and a seaming roller mechanism supported on the under side of said transverse member, said seaming roller mechanism comprising two seaming rollers arranged to be brought into seaming position opposite the rim of said chuck plate, a seaming roller driving member supported on said frame, and a driving connection between said seaming rollers and said driving member, said driving connection permitting adjustment of the range of the forward movement of the seaming rollers.

10. In a can seaming machine of the class described, a supporting frame, a removable transverse member on one side of the frame, a driving chuck plate mounted on said transverse member, a lifter plate on said frame opposite said chuck plate, means supported on said transverse member for rotatably driving said chuck plate, and a seaming roller mechanism supported on the under side of said transverse member, said seaming roller mechanism comprising a supporting member, a pair of seaming rollers arranged to be guided on said supporting member for forward movement into seaming position against the rim of said chuck plate, a seaming roller driving member for alternately bringing either one or the other of said seaming rollers into forward seaming position, means for limiting the range of movement for said driving member to vary the limit of the forward positions of said seaming rollers, and an adjustable driving connection between said seaming rollers and said driving member.

11. In a can seaming machine of the class described, a supporting frame, a transverse member on one side of the frame, a driving chuck plate mounted on said transverse member, a lifter plate on said frame opposite said chuck, means supported on said transverse member for rotatably driving said chuck plate, and a seaming roller mechanism supported on the under side of said transverse member, said seaming roller mechanism com-

prising a supporting member, a pair of seaming rollers arranged to be guided on said supporting member for forward movement into seaming position against the rim of said 5 chuck plate, a seaming roller driving member for alternately bringing either one or the other of said seaming rollers into forward seaming position, means for limiting the range of movement for said driving member 10 to vary the limit of the forward positions of said seaming rollers, and a link driving connection between said seaming rollers and said driving member.

12. In a can seaming machine of the class 15 described, a supporting frame, a removable transverse member on said frame, a driving chuck plate mounted on said transverse member, a lifter plate on said frame, opposite said chuck plate, means supported on 20 said transverse member for rotatably driving said chuck plate, and a seaming roller mechanism supported on the under side of said transverse member, said seaming roller mechanism comprising a supporting member, 25 a pair of seaming rollers arranged to be guided on said supporting member for forward movement into seaming position against the rim of said chuck plate, a seaming roller driving member for alternately bringing either one or the other of said seaming 30 rollers into forward seaming position, means for limiting the range of movement for said driving member to vary the limit of the forward positions of said seaming rollers, a 35 link connection between said driving member and said seaming rollers, and means for adjustably fixing the connection between said links and said driving member to vary the range of the forward movement of said 40 rollers.

13. In a can seaming machine of the class 45 described, a supporting frame, a transverse member on one side of the frame, a driving chuck plate mounted on said transverse member, a lifter plate on said frame opposite said 50 chuck plate, means supported on said transverse member for rotatably driving said chuck plate, and a seaming roller mechanism supported on the under side of said transverse member, said seaming roller mechanism comprising a supporting member, a 55 pair of seaming rollers arranged to be guided on said supporting member for forward movement into seaming position against the rim of said chuck plate, a seaming roller driving member for alternately bringing either one or the other of said seaming rollers into forward seaming position, means for 60 limiting the range of movement for said driving member to vary the limit of the forward positions of said seaming rollers, a link connection between said driving member and said seaming rollers, and means for 65 adjustably fixing the connection between said links and said driving member to in-

dependently vary the range of the forward movement of said rollers.

14. In a can seaming machine, a supporting member, a plurality of carrier members movably supported on said supporting member, a seaming roller on each of said carrier members, each of said carrier members being independently movable between a forward position wherein the associated seaming roller is in seaming position and the rear position wherein the seaming roller is out of seaming position, a driving lever pivotally mounted on said supporting member, a plurality of links individually connecting said driving lever to said carrier members arranged to alternately bring said rollers into seaming position, and means for independently limiting the range of the forward movement of each of said rollers. 70

15. In a can seaming machine, a supporting member, a plurality of carrier members movably supported on said supporting member, a seaming roller on each of said carrier members, each of said carrier members being independently movable between a forward position wherein the associated seaming roller is in seaming position and the rear position wherein the seaming roller is out of seaming position, a driving lever pivotally mounted on said supporting member, a plurality of links individually connecting said driving lever to said carrier members arranged to alternately bring said rollers into seaming position, and means for independently limiting the range of the forward movement 80 of each of said rollers, and means for adjustably varying the range of the angular movement of said lever. 90

16. In a can seaming machine, a supporting member, a plurality of carrier members movably supported on said supporting member, a seaming roller on each of said carrier members, each of said carrier members being independently movable between a forward position wherein the associated seaming roller is in seaming position and the rear position wherein the seaming roller is out of seaming position, a driving lever pivotally mounted on said supporting member, a plurality of links individually connecting 100 said driving lever to said carrier members arranged to alternately bring said rollers into seaming position, and means for independently limiting the range of the forward movement of each of said rollers, and means for adjustably varying the range of the angular movement of said lever. 105

17. In a can seaming machine of the class 115 described, a supporting frame, a transverse member on one side of the frame, a driving chuck plate mounted on said transverse member, a lifter plate on said frame opposite said chuck plate, means supported on said member 120

for rotatably driving said chuck plate, a pair of roller carriers movably supported on said frame, a seaming roller on each of said carriers, said carriers being independently movable in a plane substantially parallel to the plane of said chuck plate into a seaming position against the rim of said chuck plate, a driving lever pivotally mounted in said frame, and an independent link connection between each of said carriers and said driving lever arranged to alternately bring said seaming rollers into seaming position upon predetermined angular movement of said driving lever, means for independently determining the limit of the forward movement of each of said rollers into seaming position.

5 10 15

18. In a can seaming machine of the class described, a supporting frame, a transverse member on one side of the frame, a driving chuck plate mounted on said transverse member, a lifter plate on said frame opposite said chuck plate, means supported on said frame for rotatably driving said chuck plate, a pair of roller carriers movably supported on said frame, a seaming roller on each of said carriers, said carriers being independently movable in a plane substantially parallel to the plane of said chuck plate into a seaming position against the rim of said chuck plate, a driving lever pivotally mounted in said frame, and an independent link connection between each of said carriers and said driving lever arranged to alternately bring said seaming rollers into seaming position upon predetermined angular movement of said driving lever, means for independently determining the limit of the forward movement of each of said rollers into seaming position, and means for adjustably varying the range of the angular movement of said lever.

20 25 30 35 40

19. In a can seaming machine of the class described, a supporting frame, a transverse member on one side of the frame, a driving chuck plate mounted on said transverse member, a lifter plate on said frame opposite said chuck plate, means supported on said frame for rotatably driving said chuck plate, a pair of roller carriers movably supported on said frame, a seaming roller on each of

said carriers, said carriers being independently movable in a plane substantially parallel to the plane of said chuck plate, into a seaming position against the rim of said chuck plate, a driving lever pivotally mounted in said frame, and an independent link connection between each of said carriers and said driving lever arranged to alternately bring said seaming rollers into seaming position upon predetermined angular movement of said driving lever, means for independently determining the limit of the forward movement of each of said rollers into seaming position, and means for adjustably varying the connections of said links between said driving lever and said carrier members to independently vary the range of the movement of said rollers.

55 60 65

20. In a can seaming machine of the class described, a supporting frame, a transverse member on one side of the frame, a driving chuck plate mounted on said transverse member, a lifter plate on said frame opposite said chuck plate, means supported on said frame for rotatably driving said chuck plate, a pair of roller carriers movably supported on said frame, a seaming roller on each of said carriers, said carriers being independently movable in a plane substantially parallel to the plane of said chuck plate into a seaming position against the rim of said chuck plate, a driving lever pivotally mounted in said frame, and an independent link connection between each of said carriers and said driving lever arranged to alternately bring said seaming rollers into seaming position upon predetermined angular movement of said driving lever, means for independently determining the limit of the forward movement of each of said rollers into seaming position, and means for adjustably varying the range of the angular movement of said lever, and means for adjustably varying the connections of said links between said driving lever and said carrier members to independently vary the range of the movement of said rollers.

70 75 80 85 90 95

In testimony whereof I have hereunto subscribed my name this 7th day of March, 1928.

JULES WERY.
